NETTING SUPPORT FOR COTS

Cyrus M. Walker, Kansas City, Mo.

Application July 2, 1937, Serial No. 151,599

6 Claims. (Cl. 135—5.1)

This invention relates to a net and net support for folding cots, beds and the like, and has for its principal object to provide a construction of this character that is readily applied to an existing type of folding cot, and which may be removed and folded with the cot for transportation and storage purposes.

Other important objects of the invention are to provide a net support constructed to retain the net in taut condition; to provide a support which is relatively inexpensive to manufacture; to provide a support that is readily adjusted for attachment to the cross bar of a cot; and to provide a support shaped so that the side walls of the tent are kept in contact with the sides of the cot.

It is also an important object of the invention to provide a net with attached pockets to engage over the supports, thereby relieving wear and tear on the netting.

In accomplishing these and other objects of the invention, as hereinafter pointed out, I have provided improved details of structure, the preferred form of which is illustrated in the accompanying drawing, wherein:

Fig. 1 is a perspective view of a folding cot equipped with a net and net support, embodying the features of the present invention, part of the netting being broken away to better illustrate the pocket for retaining the netting on the cross bar of the support.

Fig. 2 is a fragmentary perspective view of a portion of the net as viewed from the interior thereof, particularly illustrating the pocket.

Fig. 3 is an enlarged perspective view of one of the supports.

Fig. 4 is a detailed perspective view of one corner of the cot illustrating application of the support to the cross bar of the cot.

Referring more in detail to the drawing:

I designates an ordinary folding cot, including parallel side bars 3 and 4, each comprising end sections 5 and 6 hinged together at the center of the cot, as indicated at 7. Secured to the side bars is a canvas covering 8 having hemmed ends 9 and 10 to form pockets for passing cross bars 11 and 12 at the head and foot ends of the cot. The cot is supported adjacent its ends and center on the crossed legs 13 and 14 pivoted together so that they may be folded parallel with the side bars when the cot is folded for storage or transportation purposes. The side bars are provided with dowels 15, projecting from the ends thereof to engage in openings 16 of the cross bars 55 when the cot is erected. The ends of the cross

bars project beyond the side bars as shown at 17—18, Fig. 1. The cot thus described is of standard construction and specifically forms no part of the invention, but is illustrated to give a better understanding of the present invention as now to be described.

19 designates a net including a top 20 having depending side walls 21—22 and end walls 23—24 to form a rectangular enclosure for protecting the occupant of the cot. The top 20 of the netting is of smaller dimensions than the length and width of the cot so that the side and end walls are adapted to hang smoothly in close contact with the side and end bars as shown in Fig. 1.

Secured at the juncture of the end walls with the top are pockets 25—26 extending across the width of the top. The pockets are formed by folding a strip of fabric material along the median line thereof to form side portions 26—27, which are stitched together at the ends to form 20 downwardly opening recesses to receive the supporting members later described. The folded portions of the strips are secured to the netting by lines of stitching or the like as indicated at 29, Fig. 2, so that the pockets form a permanent 25 part of the net. One of the side walls of the net, for example 21, is formed in two sections 30—31, having overlapping ends 32—33 to provide an opening 34.

35 and 36 designate supports for the net, each 30 of which includes a cross bar 38 corresponding in length to the pockets. The cross bars 38 have round ends 39—40 and pivoted thereto by pins 41—42 are similarly rounded ends 43—44 of upright bars 45—46, the bar 45 being attached to 35 one side of the cross bar, and the bar 46 to the other, so that when the bars are moved into folded position one of the bars extends along one side of the cross bar, and the other along the opposite side. The upright bars are of a length 40 to properly space the top of the net from the cover of the cot, and the lower ends thereof have loop-like clamps 47—48; the clamps being formed by bending the bars laterally as at 49, then downwardly as at 50 and again laterally as at 51, 45 thence upwardly as at 52 to the plane of the lateral bar 49 where the bar is again bent as at 53, and thence upwardly at 54 so that the terminal ends 55 thereof extend substantially parallel with the upper portion of the bars. 50

The loop-like openings 56 formed by the bends are of slightly smaller dimensions than the cross-sectional dimensions of the cross bars of the cot, to leave a space 57 between the terminal ends 55 and the upper portions of the bars. Slidable 55

upon the upper portion of the bars and engageable over the terminal ends 55 are clamping loops 58 to draw the loop-like clamps into clamping engagement with the ends of the cross bar, as 5 shown in Fig. 4. The bends are preferably formed so that the upper portion and terminal end 55 of the bars extend upwardly from the median line of the clamps.

In order to stretch the net the bars are preferably bent outwardly, as indicated at 59—60, 10 so that the cross bars 38 of the respective supports are normally spaced a greater distance than the length of the net.

In applying the supports constructed and assembled as described, the loops 58 are moved 15 upwardly out of engagement at the terminal ends 55. There is then sufficient tension in the metal so that the loop portions expand to permit sliding thereof over the projecting ends 17—18 of the cross bars of the cot. The terminal ends 55 are 20 then pressed against the upper portion of the bars so that the loops may be slid thereover to draw the clamps into clamping engagement with the cross bars of the cot. The net is then extended over the supports in such a manner that 25 the cross bars 38 engage in the pockets 25 and 26.

When the net is applied to the supports the side 30 and end walls hang in close contact with the bars of the cot so as to close the spaces therebetween. The netting is readily removed by withdrawing the pockets from the supports after which loops 58 are again released so that the supports may be withdrawn from the ends of the cross bars.

35 The upright bars 45—46 are then free to be moved into juxtaposition with the cross bar 38 to complete folding of the supports. The folded supports, together with the net, may be contained within the cot when the cot is folded for storage or transportation purposes without increasing the bulk thereof.

40 From the foregoing it is obvious that I have provided a net and net support which are readily applied to a conventional cot and which are rigidly retained in functional position when applied.

45 What I claim and desire to secure by Letters Patent is:

1. A netting support for cots including pairs 50 of upright bars having ends bent to form loops of a shape approximately conforming to the cross-section of the cross bars of a cot and having terminals extending alongside of and normally spaced from the body portions of said upright bars, retaining loops slidable on the body portions of the upright bars and movable over said terminals to contract said loop portions of the upright bars about the cross bars of the cot, and a cross bar hingedly connecting said upright bars of each pair.

60 2. A netting support for cots including pairs of upright bars having ends bent to form loops of a shape approximately conforming to the cross-section of the cross bars of a cot and having terminals extending alongside of and normally

spaced from the body portions of said upright bars, retaining loops slidable on the body portions of the upright bars and movable over said terminals to contract said loop portions of the upright bars about the cross bars of the cot, and a cross bar hingedly connecting said upright bars of each pair, the body portions of the upright bars projecting above said terminals being bent outwardly at an angle to the loop engaged portions of said upright bars for stretching a netting 10 mounted on said support.

3. A netting support for cots including pairs of upright bars having ends bent to form loops of a shape approximately conforming to the cross-section of the cross bars of a cot and having terminals extending alongside of and normally spaced from the body portions of said upright bars, retaining loops slidable on the body portions of the upright bars and movable over said terminals to contract said loop portions of the upright bars about the cross bars of the cot, and a cross bar of less length than the cross bars of the cot having its ends connected with the upright bars whereby sides of the netting are caused to closely contact the sides of the cot.

4. A covering for cots including a netting having interconnected top, side and end walls, downwardly opening fabric pockets extending coextensively along the juncture of the end walls with the top, a support for the netting including spaced uprights engageable in the corners of the netting, cross bars spacing the upper ends of the uprights and received in said pockets to tighten the netting in a transverse direction, and means on the uprights to clamp the uprights to 30 the cross bars at the respective ends of the cot, said uprights at the respective ends of the cot diverging outwardly to stretch the netting in a longitudinal direction.

5. A netting for cots comprising a substantially rectangular top of smaller longitudinal and transverse dimensions than the corresponding dimensions of the cot, side and end walls connected with the top, supports for tightening said top horizontally of the cot, the lower portions of said side and end walls respectively corresponding to the length and width of the cot whereby the side and end walls are caused to closely drape over the sides and ends of the cot, and fabric pockets extending coextensively with the ends 50 of said top for receiving said supports.

6. A cover for cots including a netting having interconnected top, side and end walls, downwardly opening fabric pockets arranged coextensively along the juncture of the end walls with the top, a support for the netting including spaced uprights engageable in the corners formed between the end and side walls, cross bars spacing the upper ends of the uprights and received in said pockets to tighten the netting in a transverse direction, and means on the uprights to clamp the uprights to the cross bars at the respective ends of the cot.

CYRUS M. WALKER.
